[57] CLAIM

The ornamental design for an actuator housing, as shown and described.

DESCRIPTION

FIG. 1 is a front perspective view of an actuator housing showing my new and ornamental design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of a base and connecting rods in FIG. 1 and connector and plug in FIGS. 1-4 and 7 is for illustrative purposes only and forms no part of the claimed design.

FIG. 2

FIG. 3

FIG. 4

FIG. 5

FIG. 6

FIG. 7
